PRODUCTION OF CYCLIC MONO-SULFONES

Rupert C. Morris and Harry de V. Finch,
Berkeley, Calif., assignors to Shell Develop-
ment Company, San Francisco, Calif., a corpo-
ration of Delaware

No Drawing. Application June 15, 1943,
Serial No. 490,931

6 Claims. (CL 260—329)

1

This invention relates to the production of cyclic mono-sulfones, and more particularly pertains to a novel process for the economical production of high yields of 3-sulfolene and of its substituted derivatives by the interaction of sulfur dioxide with poly-olefinic organic compounds containing at least two olefinic linkages in conjugated relationship.

It is well known that cyclic mono-sulfones are valuable compounds which may be used as such in various organic syntheses, for example as intermediates for the manufacture of organic dye-stuffs and textile assistants. Also, at least some of the cyclic sulfones, such as 2,4-dimethyl-4-sulfolene, are suitable as solvents for the selective solvent extraction of various organic mixtures. Furthermore, it is known that cyclic mono-sulfones may be readily decomposed into sulfur dioxide and the poly-olefin employed in the original production of the sulfone, such decomposition being usually effected by simple heating of the cyclic mono-sulfone or sulfones, preferably at a subatmospheric pressure. This characteristic of cyclic mono-sulfones affords a ready method for the separation of poly-olefins from the corresponding more saturated hydrocarbons. For instance, it is known that hydrocarbon fractions, even when they boil within a relatively narrow range, consist of a number of different hydrocarbons having different structures, possessing different properties and characteristics, and suitable for different uses, particularly due to the difference in the degree of saturation of the various constituents of such hydrocarbon fractions. As an example, when a hydrocarbon fraction formed by the pyrolysis of hydrocarbons of the type of naphtha, kerosene, stove oil or the like, is fractionally distilled to recover separately a fraction boiling between about 25° C. and about 50° C. to 55° C., this narrow boiling fraction will predominate in various olefins having five carbon atoms per molecule. Besides the different straight and branched chain mono-olefins having five carbon atoms per molecule, this fraction will also contain greater or lesser concentrations of diolefins, e. g. isoprene and piperylene, as well as cyclopentadiene. These different olefins, and particularly the diolefins, are suitable for various purposes and may be used in various industries, so that their separate recovery from the hydrocarbon fractions consisting of or predominating in the various olefin hydrocarbons having five carbon atoms per molecule, is highly desirable. Similarly, a slightly higher boiling fraction of hydrocarbons formed by the aforementioned

pyrolysis (which fraction may boil between about 55° C. and about 80° C.) will predominate in various olefins having six carbon atoms per molecule and may contain, besides the different hexenes

5 (i. e., straight chain or branched chain mono-olefins having six carbon atoms per molecule), various hexadienes and particularly the branched-chain hexadienes, such as 2-methyl pentadiene-1,3 and 4-methyl pentadiene-1,3. 10 These branched-chain dienes are very valuable products, being highly suitable as an ingredient in the manufacture of synthetic rubber. Also, the cyclic monosulfones formed by the interaction of these methyl pentadienes with sulfur dioxide, 15 when hydrogenated are highly suitable as selective solvents.

It has been previously proposed to separate cyclic diolefins from narrow boiling olefin-containing or olefin-predominating hydrocarbon 20 fractions by contacting such fractions, at elevated temperatures and pressures, with sulfur dioxide to form the sulfones of the acyclic diolefins. The chief difficulty of this method lies in the fact that instead of forming cyclic mono-olefins which 25 upon heating readily decompose to yield substantially quantitative amounts of the diolefins, a reaction between the acyclic diolefins and sulfur dioxide tends toward the formation of insoluble, amorphous products which do not readily yield 30 the diolefins when subjected to ordinary processes of decomposition. The amorphous compounds are poly-sulfones, while the compounds which may be readily decomposed into the starting materials, namely sulfur dioxide and the poly-olefins, are the cyclic mono-sulfones, i.e. monomeric poly-olefin sulfones.

Although it has been previously proposed to 35 avoid the formation of the amorphous poly-sulfones during the interaction between poly-olefins and sulfur dioxide, all of the known processes of inhibiting such poly-sulfone formation are 40 attended by certain difficulties which render their use uneconomical or undesirable. For instance, it has been previously proposed to inhibit 45 the formation of the amorphous sulfones by the use of certain halogen-containing substances such as hydrogen halides. The use of such acids is undesirable because of their tendency to react with the olefins present in the hydrocarbon mixtures subjected to the action of sulfur dioxide. 50 Also, the presence of halogen compounds makes the subsequent hydrogenation of the sulfones impossible, at least as far as the use of nickel hydrogenation catalysts is concerned. It has 55 also been proposed to inhibit the formation of

amorphous poly-sulfones by avoiding the presence of a large excess of the sulfur dioxide in the reaction zone. In accordance with this process the poly-olefins or poly-olefin-containing hydrocarbon fractions are treated at suitable temperatures and pressures with relatively small amounts of sulfur dioxide, e. g. less than half the amount necessary to react with the diolefins present in the reaction zone. It is obvious that such a treatment, if effected in a batch process, does not result in the separation of all of the poly-olefins. If effected in a continuous or intermittent system, such use of relatively small amounts of sulfur dioxide necessitates the repeated recycling of the hydrocarbon fractions into the reaction zone, thus increasing the cost of operation and requiring relatively long periods of time for the effecting of the desired conversion of the poly-olefins to the corresponding cyclic mono-olefins. The term "sulfolene" as used in this specification is understood to mean the chemical compound thiocyclopentene-1,1-dioxide and the term "a sulfolene" is understood to mean a substituted derivative thereof wherein one or more of the hydrogen atoms are substituted by various radicals or elements.

It is an object of the present invention to avoid the above and other defects and to provide an economical process for the efficient conversion of unsaturated organic compounds containing two or more double linkages, and particularly those containing at least two olefinic linkages in conjugated position, to the corresponding cyclic mono-sulfones. It is another object of the invention to provide a process whereby cyclic mono-sulfones may be readily and rapidly formed in high yields while avoiding or at least greatly inhibiting the formation of the undesirable amorphous poly-sulfones which, as stated, are usually formed when poly-unsaturated organic compounds, e. g. poly-olefins, are reacted with sulfur dioxide under conditions favoring the formation of sulfones.

In some cases, e. g., when 2-methyl pentadiene-1,3 and/or 4-methyl pentadiene-1,3, or hydrocarbon fractions containing these or other like diolefins, are reacted in the known manner with sulfur dioxide, it is found that there occurs a polymerization of these diolefins instead of a formation of the desired cyclic mono-sulfones or even of the undesirable poly-sulfones. It is therefore a still further object of the present invention to provide a process wherein the polymerization of the diolefins is inhibited, and wherein the interaction between such poly-olefins and the sulfur dioxide results in a substantially quantitative conversion of the acyclic poly-olefins to the corresponding cyclic mono-sulfones.

It has now been discovered that the above and other objects may be attained by the use of poly-unsaturated organic compounds, e. g. poly-olefins or poly-olefin-containing hydrocarbon fractions which are substantially free from peroxides. Broadly stated, it has been discovered that it is possible to effect a rapid reaction between sulfur dioxide and poly-olefins, particularly those containing at least two olefinic linkages in conjugated position, to produce high yields of the desired cyclic mono-sulfones and at the same time inhibit side reaction, e. g. polymerization and/or formation of the undesirable amorphous, difficultly decomposable poly-sulfones, by employing poly-olefins or poly-olefin-containing hydrocarbon fractions which are free or substantially free of peroxides and by using sulfur dioxide in amounts

greatly in excess of the amount necessary to combine with all of the poly-olefins present in the reaction zone. When the hydrocarbon fraction subjected to the action of sulfur dioxide in accordance with the process of the present invention is free or substantially free from peroxides, the use of large amounts of sulfur dioxide, i. e. amounts greatly in excess of those necessary to combine with the poly-olefins, does not tend to form the undesirable amorphous poly-sulfones or cause the polymerization of the poly-olefins, but merely permits a more rapid reaction between the poly-olefins and the sulfur dioxide, and results in high and even substantially quantitative yields of the desirable mono-sulfones.

Although the process of the present invention is applicable to the reaction of sulfur dioxide with various poly-unsaturated organic compounds, it is particularly suitable for the treatment of straight chain and/or branched chain unsaturated hydrocarbons containing at least two olefinic linkages in conjugated position, i. e. compounds having the general structural formula

in which the substituents R₁ to R₆ inclusive are selected from the group consisting of the hydrogen atom and the alkyl, alkenyl, aryl, alkaryl, aralkyl, cyclo-alkyl and cyclo-alkenyl groups or radicals. As suitable aliphatic poly-olefins which may be converted to the corresponding cyclic mono-sulfones in accordance with the process of the present invention, reference may be made to the diolefins with conjugated double bonds such as butadiene-1,3, 2-methyl butadiene-1,3 (isoprene), pentadiene-1,3 (piperylene), 2,3-dimethyl butadiene-1,3, 2,3-diethyl butadiene-1,3, 2,3-di-tertiary-butyl butadiene-1,3, 2-tertiary-butyl butadiene-1,3, 1,2,3,4-tetramethyl butadiene-1,3, 1,4-dimethyl-2,3-diethyl butadiene-1,3, 2-methyl pentadiene-1,3, 4-methyl pentadiene-1,3, 2-methyl hexadiene-1,3, 4-ethyl hexadiene-1,3, and the like, and their homologues and analogues. Compounds having more than two double bonds, particularly when these olefinic linkages are in conjugated relationship, are also suitable compounds which may be treated with sulfur dioxide in accordance with the process of the present invention. The straight chain poly-olefins of the class described above may also have cyclo-alkyl, cyclo-alkenyl, and/or aromatic radicals linked to carbon atoms of primary, second and/or tertiary character, examples of such compounds being cyclo-pentyl butadienes, cyclopentyl pentadienes, cyclohexyl butadienes, 2-phenyl butadiene-1,3, 2,3-diphenyl butadiene-1,3, and the like and their homologues and analogues. Also, suitable substituted derivatives of the above and like poly-olefins may be reacted with sulfur dioxide to form the desired mono-sulfones, examples of such substituted poly-olefins being 2-chlorbutadiene-1,3, 2-methyl-3-chlorbutadiene-1,3, 1-cyano butadiene-1,3, and the like.

The invention may therefore be stated to reside in a process of producing cyclic sulfones by reacting substantially peroxide-free unsaturated organic compounds of the class defined above with sulfur dioxide employed in an amount greatly in excess of that necessary to react with the poly-olefins or poly-olefinic compounds, this reaction being effected under the hereinbelow described operating conditions favoring the for-

mation of the sulfones. The use of the large amounts of sulfur dioxide permits a rapid reaction, while the absence of peroxides in the reaction mixture inhibits or at least greatly reduces the tendency towards formation of the undesirable amorphous polysulfones and/or of hydrocarbon polymers, so that the execution of the process results in a rapid and economical production of high yields of the desired cyclic monosulfones.

It is known that unsaturated organic compounds, and particularly those containing a plurality of conjugated double bonds, readily tend to form organic peroxides upon standing, especially when such unsaturated compounds are exposed to the action of light and/or air. The separation of these organic peroxides from the unsaturated compounds may be effected by a plurality of well-known processes. It has been found that a particularly suitable method for the separation and recovery of substantially peroxide-free unsaturated organic compounds from unsaturated compounds which have been exposed to the action of air and/or light, which unsaturated compounds therefore contain greater or lesser concentrations of the organic peroxides, may be effected by subjecting the peroxide-containing mixtures to a distillation in the presence of a strong base or of a basic-acting compound, the use of the latter during such distillation preventing dangerous explosions which frequently occur when peroxide-containing mixtures are subjected to ordinary distillations in the absence of such basic compound. Strong bases such as alkali metal hydroxides of the type of sodium hydroxide may be employed either as such or in the form of their aqueous or alcoholic solutions. The amount of the basic or basic-acting material to be added to a given unsaturated fraction to be subjected to distillation will vary depending on the specific basic or basic-acting compound employed, the particular unsaturated compound to be distilled, and the amount or concentration of the organic peroxides in the fraction to be purified. Generally, it has been found that aqueous sodium hydroxide solutions may be used in amounts ranging from about 5% to about 20% by volume of the unsaturated organic fraction to be treated. However, greater or lesser amounts of such basic or basic-acting compound may also be employed. The mixtures of the unsaturated compound to be treated and of the basic material may be subjected to flash distillation, the temperature being that at which the peroxide-free unsaturated compound or compounds will be vaporized so that they may be recovered as an overhead fraction. When relatively high boiling unsaturated compounds are to be thus purified, it is preferred to employ subatmospheric pressures to prevent polymerization and/or other undesirable side reactions. Since the unsaturated compounds, e. g. olefins, and particularly the fractions which contain relatively high percentages of poly-olefins, are, as stated above, quite reactive and will tend to form organic peroxides even by a mere contact with air and/or light even at ordinary temperatures and pressures, it is essential to prevent any further formation of the organic peroxides in the interim between the purification step and the time when the peroxide-free fraction is reacted with sulfur dioxide under conditions favorable to the formation of the cyclic mono-sulfones by the interaction of the sulfur dioxide with the poly-olefins or poly-unsaturated organic compounds

present therein. This may be effected by reacting the peroxide-free fractions with the sulfur dioxide substantially immediately after the removal of the peroxides therefrom, by the addition of various inhibitors such as pyrogallol, hydroquinone, pyrocatechol, tertiary-butyl catechol, or the like, to the purified fraction, by storage in an inert atmosphere, or by using other known means or methods of inhibiting peroxide formation. It must be noted at this point that the addition of the inhibitors of the class described above does not inhibit the formation of the desired mono-sulfones during the interaction between the sulfur dioxide and the peroxide-free unsaturated compound.

Although generally speaking the mol ratio of the sulfur dioxide to the poly-olefins may vary within relatively wide limits, it has been pointed out above that high yields of the desired monomeric cyclic sulfones are obtainable when the sulfur dioxide is employed in amounts greatly in excess of those necessary for the conversion of all of the poly-olefins into the corresponding cyclic mono-sulfones. As long as the poly-olefinic organic compounds are free or substantially free from organic peroxides, an increase in the mol ratio of the sulfur dioxide to the poly-olefinic organic compounds, other conditions being maintained equal, will increase the yield of the cyclic unsaturated mono-sulfones obtained when such mixtures of the sulfur dioxide and of the poly-olefinic organic compound or compounds are subjected to temperature and pressure conditions favoring the interaction between these reactants.

For example, other conditions being maintained equal, by increasing the mol ratio of sulfur dioxide to isoprene from about 2:1 to about 4:1 it is possible to raise the yield of the isoprene sulfone (3-methyl-3-sulfolene) from about 78% to 89.5%. This increase in the yield of the mono-sulfones is effected in accordance with the process of the present invention without the use of any catalysts and/or restraining agents, the sole requirement being that the poly-olefin-containing hydrocarbon fraction must be free from organic peroxides. As pointed out above, this discovery is contrary to well-accepted opinions to the effect that the use of sulfur dioxide in excess of the amount necessary to combine with the acyclic di-olefins tends to form insoluble, amorphous addition products, i. e. poly-sulfones. As stated, and contrary to the above mentioned previous opinions, the use of sulfur dioxide in amounts in excess of those necessary to combine with all of the poly-olefinic organic compounds present in the reaction mixture will increase the yield of the cyclic mono-sulfones without any substantial formation of the insoluble, amorphous poly-sulfones and without any substantial polymerization of the unsaturated hydrocarbons if the reactants are free or substantially free from organic peroxides. It has been discovered that satisfactorily high yields of the desirable mono-sulfones may be obtained when the reaction mixture contains sulfur dioxide in an amount which is equal to about four mols per mol of the poly-olefinic compounds present in the mixture. However, greater or lesser ratios may also be employed. Ratios below about 2:1 should, however, be generally avoided because of the fact that the yields of the desired mono-sulfones may become so low as to render the process uneconomical. Also, excessively high ratios, e. g. those above about 10:1, should be avoided because of the excessive dilution of the

poly-olefins and/or the necessity of using uneconomically large units.

The reaction between the above-outlined poly-olefinic organic compounds, such as the diolefins containing the double bonds in conjugated position, and the sulfur dioxide to form the unsaturated cyclic sulfones, i. e. sulfolene and its derivatives, is preferably effected while maintaining the reactants in the liquid phase or at least under such conditions that the reactants are predominantly in the liquid state. Generally, the reaction temperature should be maintained in the neighborhood of 100° C., although somewhat higher or lower temperatures may also be employed. The optimum reaction temperature depends at least in part upon the specific poly-olefinic organic compound treated. When the operating temperature drops too low, the addition reaction, even in the case of those poly-olefinic compounds which have a relatively high reaction rate with respect to the desired addition reaction, becomes so low as to render the process uneconomical. Also, the use of such low temperatures frequently increases the yield of the undesirable poly-sulfones. On the other hand, care should be taken to avoid the use of temperatures which are sufficiently high to cause the decomposition of the formed mono-sulfones back to the starting reactants.

Although the sulfone formation reaction may be effected at pressures which are only sufficient to maintain the reactants in the liquid state at the operating temperature employed, higher pressures may also be used. Generally the reaction pressure is higher than that at which the reactants are introduced into the reaction vessel. This is due to the fact that it is usually preferable to effect the introduction of reactants into the reaction vessel or autoclave at or below ordinary temperatures in order to maintain the reactants in the liquid state during such introduction, whereas the reaction temperature, as stated, is in the neighborhood of about 100° C. The reaction pressures thus generated in the autoclave are between about 100 pounds per sq. in. and about 500 pounds per sq. in., or even higher, depending in part on the specific poly-olefinic compound or compounds treated. The residence time will vary depending on the specific poly-olefinic organic compound or compounds which are reacted with sulfur dioxide to effect the formation of the desired corresponding unsaturated cyclic mono-sulfone or sulfones.

It was pointed out above that the monomeric sulfones find utility in various industries and may be used either as such, e. g. as solvents, or may be employed as intermediates in the manufacture of various other chemical compounds. It was also brought out above that the various sulfolenes, i. e. unsaturated cyclic monomeric sulfones, may be readily decomposed to form mixtures comprising or consisting of sulfur dioxide and the starting unsaturated compound or compounds by subjecting the sulfolenes to temperatures which favor their decomposition. This permits the use of the sulfone-formation step for the separation of the poly-olefins from mixtures containing them and other more saturated organic compounds. In such a case, after the termination of the addition reaction between the sulfur dioxide and the poly-olefinic organic compounds, e. g. poly-olefinic hydrocarbons containing two olefinic linkages in conjugated position, the sulfolenes may then be separated from the unreacted hydrocarbons, if any, and from the excess sulfur dioxide,

and these mono-sulfones may then be decomposed to liberate the sulfur dioxide and recover the poly-olefinic compound which originally reacted with the sulfur dioxide to form the sulfolenes. This decomposition may be effected, for example, by heating the separated sulfolenes to a temperature sufficiently high to cause the decomposition thereof. As a general rule this heating should be effected under reduced pressures in order to inhibit or prevent the polymerization of the poly-olefinic compounds thus liberated. However, with certain of the sulfolenes, it is possible to effect their decomposition at atmospheric pressure. Obviously the decomposition temperature will vary depending on the specific sulfolene treated, as well as on the pressure employed. For instance, when effected at or about atmospheric pressure, the decomposition of 2,4-dimethyl-3-sulfolene necessitates a temperature of between about 120° C. and about 130° C., while the use of a reduced pressure, e. g. of the order of about 50 mm. of mercury pressure, permits decomposition at temperatures of between 80° C. and 120° C. The separation of the obtained poly-olefin from the reaction product may be effected by any known means. For example, when the decomposition of the unsaturated cyclic sulfones, i. e. sulfolenes, is effected by distillation, the overhead gaseous fraction may be conveyed through scrubbers containing an alkaline solution, e. g. a 10% aqueous solution of sodium hydroxide, which removes the liberated sulfur dioxide, the remaining gaseous fraction comprising or consisting of the original poly-olefinic compounds which reacted with the sulfur dioxide to form the sulfolenes, or at least structural isomers of such poly-olefinic compounds. Another method of separating the sulfur dioxide from the diolefins comprises scrubbing the overhead gaseous mixture with a liquid hydrocarbon oil such as a high boiling naphtha, kerosene, or gas oil, which selectively dissolves the poly-olefins. The latter may then be separated from the solvent by any known means. This method of separation is described more fully in U. S. Patent No. 2,264,878.

The invention is further illustrated by the following specific examples, it being understood that there is no intention of being limited by any details thereof, since many apparent variations may be made.

Example I

A hydrocarbon fraction comprising butylenes and butadiene-1,3, which fraction was found to contain about 42 weight percent of the butadiene and some organic peroxides, was employed. This hydrocarbon fraction and sulfur dioxide were then separately liquefied by chilling and maintaining them at a superatmospheric pressure of about 20 pounds per sq. in. gage. The reactants were then introduced into an evacuated bomb reactor which was chilled by means of a solid carbon dioxide bath. Approximately 1.2 mols of liquid sulfur dioxide and about 0.9 mol of the above hydrocarbon fraction (which contained about 0.38 mol of butadiene-1,3) were thus introduced into the reactor. The mol ratio of the sulfur dioxide to the butadiene was therefore equal to about 3.14:1. The reactor was then closed and placed into boiling water so as to maintain the reaction within the reactor at about 97° C. The reaction was continued for about two hours, after which the unreacted gases were released. An analysis of the reaction products showed that approximately 86 mol per cent of the butadiene reacted to form sulfones. The

yield of the desirable cyclic mono-sulfone, i. e. 3-sulfolene, was equal to about 77.6 mol per cent.

Example II

A hydrocarbon fraction comprising butylenes and butadiene, but containing some organic peroxides, was mixed with about 10% by volume of an aqueous sodium hydroxide solution, the mixture being then subjected to flash distillation to separate a peroxide-free hydrocarbon fraction which upon analysis was found to contain about 38.2 weight per cent of butadiene-1,3. This hydrocarbon fraction and sulfur dioxide were then separately liquefied and introduced into an evacuated bomb reactor in the same manner as described in the previous example, the mol ratio of the sulfur dioxide to the butadiene in the reactor being found to be equal to about 4.17:1. The reactants were then subjected to substantially the same temperatures and pressures as those employed in the previous example, this reaction being continued for about 2½ hours. An analysis of the reaction products indicated that the total yield of sulfones was equal to about 98.8 mol percent, and that the yield of the undesirable poly-sulfones was less than 0.3%.

A comparison of the results obtained in the above two examples clearly shows the advantages which are obtained by effecting the sulfone formation in accordance with the process of the present invention. Thus the removal of the peroxides from the treated hydrocarbon fraction greatly decreased the formation of the undesirable poly-sulfones. In fact the use of peroxide-free hydrocarbons permitted the use of a higher sulfur dioxide-to-diolefin mol ratio resulted in a reaction between the sulfur dioxide and substantially all of the diolefins present in the reaction zone, and at the same time substantially inhibited the production of the undesirable poly-sulfones.

Example III

A hydrocarbon fraction boiling between 32° C. and 36° C. and produced by thermal cracking of the second cut straight run gasoline was employed. This fraction (which predominated in olefins having 5 carbon atoms per molecule) was found by analysis to contain approximately 47.5% by weight of isoprene, together with some organic peroxides which were present in the fraction in spite of the fact that it contained hydroquinone. This peroxide-containing hydrocarbon fraction and sulfur dioxide were then separately liquefied and introduced into an evacuated bomb reactor. Approximately 1.11 mols of liquid sulfur dioxide and about 0.513 mol of the above hydrocarbon fraction (which contained approximately 0.268 mol of isoprene) were thus introduced into the reactor. The mol ratio of the sulfur dioxide was therefore equal to 4.14:1. The reactor was then closed and heated to a temperature of about 99° C. for a period of about three hours. An analysis of the reaction products showed that about 61% of the isoprene reacted to produce predominantly poly-sulfones.

Example IV

A hydrocarbon fraction predominating in olefins having 5 carbon atoms per molecule and containing about 44.3 mol per cent of isoprene (the remainder being mono-olefins having 5 carbon atoms per molecule) was first distilled with a strong base to obtain an overhead hydrocarbon distillate which is free from organic peroxides. This peroxide-free hydrocarbon fraction was then liquefied and introduced into an evacuated

bomb together with liquid sulfur dioxide. Approximately 1.5 mols of liquid sulfur dioxide and a total of 0.847 mol of the above hydrocarbon fraction (which thus contained about 0.391 mol of isoprene) were introduced into the reactor. The mol ratio was therefore equal to about 3.86:1. This mixture was then treated in the same manner as that described in Example III, the reaction period being equal to about 0.5 hour. An analysis of the reaction products showed that 99.5% of the isoprene reacted with the sulfur dioxide to produce substantially only 3-methyl-3-sulfolene (isoprene mono-sulfone), the reaction products being substantially free from any poly-sulfones.

A comparison of the results of Examples III and IV clearly shows the advantages of effecting the sulfone formation in accordance with the process of the present invention, the use of the peroxide-free hydrocarbon fractions permitting faster rates of reaction, greater conversions, greater yields of desired mono-sulfone and substantial inhibition of the formation of by-products, e. g. undesirable poly-sulfones.

Example V

A hydrocarbon fraction boiling between 41° C. and 44° C. and produced by straight distillation of the product formed by cracking second cut straight run gasoline was employed. This fraction was first treated in the manner described in the previous example to remove any organic peroxides present therein. The overhead condensed distillate contained about 42.8 weight per cent piperylene. The formation of the sulfone in the above examples, the sulfur dioxide being used in a mol ratio of 4:1 and the reaction period being about two hours. After removal of the unreacted products, it was found that approximately 96.3% of the piperylene originally present in the reactor combined with the sulfur dioxide to produce 2-methyl-3-sulfolene. Substantially no poly-sulfone was formed.

Example VI

A methyl pentadiene fraction, which was stored in a drum and which was found to contain organic peroxides in spite of the presence of some p-tertiary butyl catechol, was mixed with liquid sulfur dioxide in substantially equimolecular amounts. The mixture was then introduced into an evacuated reactor, which latter was then sealed and heated for a period of about one hour at a temperature of about 100° C. The unreacted gases and vapors were then vented, and the remaining reaction product was analyzed. It was found that approximately 69% of the methyl pentadienes were converted to 2,4-dimethyl-3-sulfolene, while more than 20% of the charged methyl pentadienes were polymerized.

Example VII

A methyl pentadiene fraction obtained from the same source as that used in the preceding example was first flash distilled in the presence of a 10% aqueous sodium hydroxide solution, the distillate (which was thus free from peroxides) being then substantially immediately mixed with liquid sulfur dioxide and the mixture then treated in the same manner and under the same conditions as those described in Example VI. An analysis of the reaction product showed that the conversion to 2,4-dimethyl-3-sulfolene was equal to about 80.8%, as based on the charged methyl pentadienes, and that only about 1.5% of these

diolefins polymerized. A further improvement in the yield of the desired cyclic mono-sulfone is obtainable by increasing the mol ratio of the sulfur dioxide to the substantially peroxide-free methyl pentadiene charged into the reactor.

The above examples disclose the advantages of employing peroxide-free hydrocarbon fractions. As noted above, the presence of organic peroxides under the reaction conditions tends to form difficultly decomposable poly-sulfones and/or the polymerization of the diolefins employed. The mere addition of inhibitors of the type of pyrogallol is insufficient since they merely inhibit further formation of the peroxides and do not decompose those already present in the hydrocarbons or hydrocarbon mixtures treated. Therefore, in order to produce high yields of the desirable mono-sulfones, it is necessary to destroy these peroxides, for example by the aforementioned distillation in the presence of a strong base, or otherwise destroy and remove the organic peroxides from the hydrocarbon fraction to be subjected to the action of sulfur dioxide under temperature and pressure conditions which favor the formation of the corresponding cyclic sulfones.

This application is a continuation-in-part of the co-pending application, Serial No. 404,064, filed July 25, 1941.

We claim as our invention:

1. In a process for the production of 2,4-dimethyl-3-sulfolene while inhibiting undesirable side reactions, the steps of mixing a hydrocarbon fraction boiling between about 55° C. and about 80° C., predominating in unsaturated hydrocarbons having six carbon atoms per molecule and containing 2-methyl pentadiene-1,3 and 4-methyl pentadiene-1,3, which hydrocarbon fraction also contains organic peroxides, with an aqueous sodium hydroxide solution employed in an amount equal to about 10% by volume of the hydrocarbon fraction treated, subjecting this mixture to a distillation to obtain the hydrocarbon fraction in a substantially peroxide-free state, mixing said peroxide-free hydrocarbon fraction with liquid sulfur dioxide employed in an amount equal to about 4 mols of sulfur dioxide per mol of the methylpentadienes present in the hydrocarbon fraction treated, subjecting said mixture to a temperature in the neighborhood of about 100° C., at a superatmospheric pressure sufficient to maintain the reactants in the liquid state, and for a period of time sufficient to effect an addition reaction between the sulfur dioxide and the methylpentadienes, and separating the 2,4-dimethyl-3-sulfolene thus formed from the reaction mixture.

2. In a process for the production of high yields of 3-methyl-3-sulfolene while inhibiting the formation of poly-sulfones, the steps of mixing a peroxide-containing hydrocarbon fraction predominating in olefins having five carbon atoms per molecule and containing isoprene with an aqueous sodium hydroxide solution, subjecting the mixture to a distillation to obtain the isoprene-containing hydrocarbon fraction in a substantially peroxide-free state, mixing said peroxide-free fraction with liquid sulfur dioxide employed in an amount equal to about 4 mols of the sulfur dioxide per mol of the isoprene present in the hydrocarbon fraction treated, subjecting said mixture to an elevated temperature in the neighborhood of 100° C., at a superatmospheric pressure sufficient to maintain the reactants in the liquid state, and for a period of time sufficient to effect an addition reaction between the sulfur dioxide and the isoprene, and separating the 3-methyl-3-sulfolene thus formed from the reaction mixture.

time sufficient to effect an addition reaction between the sulfur dioxide and the isoprene, and separating 3-methyl-3-sulfolene thus formed from the reaction mixture.

3. In a process for the production of high yields of 2-methyl-3-sulfolene while inhibiting the formation of poly-sulfones, the steps of mixing a peroxide-containing hydrocarbon fraction predominating in olefins having five carbon atoms per molecule and containing piperylene, with an aqueous sodium hydroxide solution, subjecting the mixture to a distillation to obtain said hydrocarbon fraction in a substantially peroxide-free state, mixing said peroxide-free hydrocarbon fraction with liquid sulfur dioxide employed in an amount equal to about 4 mols of sulfur dioxide per mol of the piperylene present in the hydrocarbon fraction treated, subjecting said mixture to a temperature in the neighborhood of about 100° C., at a superatmospheric pressure sufficient to maintain the reactants in the liquid state, and for a period of time sufficient to effect an addition reaction between the sulfur dioxide and the piperylene, and separating 2-methyl-3-sulfolene thus formed from the reaction mixture.

4. In a process for the production of 2,4-dimethyl-3-sulfolene while inhibiting undesirable side reactions, the steps of mixing a hydrocarbon fraction containing 2-methylpentadiene-1,3, 4-methylpentadiene-1,3 and organic peroxides, with an aqueous solution of a basic-acting compound, subjecting this mixture to a distillation to obtain the hydrocarbon fraction in a substantially peroxide-free state, mixing said peroxide-free hydrocarbon fraction with liquid sulfur dioxide employed in an amount between about 2 mols and about 10 mols of sulfur dioxide per mol of the methyl pentadienes present in the peroxide-free hydrocarbon fraction, and subjecting said mixture to a temperature of about 100° C. at a superatmospheric pressure sufficient to maintain the reactants in the liquid state and for a period of time sufficient to effect an addition reaction between the sulfur dioxide and the methyl pentadienes.

5. In a process for the production of high yields of cyclic monosulfones while inhibiting undesirable side reactions, the steps of subjecting 2-methylpentadiene-1,3 containing organic peroxides to a distillation in the presence of a basic-acting compound, thereby obtaining the pentadiene in a substantially peroxide-free state, mixing said substantially peroxide-free 2-methylpentadiene-1,3 with liquid sulfur dioxide employed in an amount between about 2 mols and about 10 mols of the sulfur dioxide per mol of the methyl pentadiene, subjecting said mixture to an elevated temperature in the neighborhood of about 100° C. at a superatmospheric pressure sufficient to maintain the reactants in the liquid state and for a period of time sufficient to effect an addition reaction between the sulfur dioxide and the methyl pentadiene, and separating the 2,4-dimethyl-3-sulfolene thus formed from the reaction mixture.

6. In a process for the production of monomeric cyclic sulfones while inhibiting undesirable side reactions of the type of polymerization and formation of polysulfones, the steps of subjecting an unsaturated hydrocarbon containing at least two olefinic linkages in conjugated position, which hydrocarbon is contaminated with organic peroxides, to a distillation in the presence of a basic-acting compound to obtain said unsaturated hydrocarbon in a substantially peroxide-free state.

free state, reacting said substantially peroxide-free unsaturated hydrocarbon with sulfur dioxide employed in an amount in excess of that necessary to react with said unsaturated hydrocarbon, and effecting said reaction at a temperature of about 100° C. at a superatmospheric pressure sufficient to maintain the reactants in the liquid state and for a period of time sufficient to effect an addition reaction between the sulfur dioxide and the unsaturated hydrocarbon.
